CLAIM

The ornamental design for a picture frame or similar article, as shown and described.

DESCRIPTION

FIG. 1 is a perspective view of a picture frame or similar article showing my new design; FIG. 2 is a front elevational view thereof;

FIG. 3 is a fragmentary perspective view of the upper left side corner;

FIG. 4 is a top plan view thereof, the opposite side being a mirror image;

FIG. 5 is a right side elevational view thereof, the opposite side being a mirror image;

FIG. 6 is an enlarged fragmentary side elevational view of the upper and lower right corners of FIG. 5;

FIG. 7 is a rear elevational view thereof; and

FIG. 8 is an exploded perspective view thereof.
